UNITED STATES PATENT OFFICE

EDSELL T. BLEECKER, OF PUEBLO, COLORADO

DESIGN FOR A ROCKER

Application filed November 4, 1929. Serial No. 33,301. Term of patent 14 years.

To all whom it may concern:

Be it known that I, EDSELL T. BLEECKER, a citizen of the United States, residing at Pueblo, in the county of Pueblo and State of Colorado, have invented a new, original, and ornamental Design for a Rocker, of which the following is a specification.

The figure is a perspective view of a rocker showing my new design.

I claim the ornamental design for a rocker as shown.

In testimony whereof I have affixed my signature.

EDSELL T. BLEECKER.
